UNITED STATES PATENT OFFICE.

DAVID C. MOORE, OF CLEVELAND, OHIO.

DESIGN FOR A RADIATOR-INCLOSURE.

56,255.

Specification for Design. Patented Sept. 7, 1920.

Application filed April 15, 1920. Serial No. 374,240. Term of patent 14 years.

To all whom it may concern:

Be it known that I, DAVID C. MOORE, a citizen of the Dominion of Canada, residing at Cleveland, in the county of Cuyahoga and State of Ohio, have invented a new, original, and ornamental Design for Radiator-Inclosures, of which the following is a specification, reference being had to the accompanying drawing, forming part thereof.

Figure 1 represents a front elevation, Fig. 2 a plan and Fig. 3 a side elevation, showing my new design.

I claim:

The ornamental design for a radiator inclosure, as shown.

Cleveland, Ohio, April 9th, 1920.

DAVID C. MOORE.
